[57] CLAIM

The ornamental design for a translucent covered multi point foot support for footwear, as shown and described.

DESCRIPTION

FIG. 1 is a top plan view of the first embodiment of the present design showing the translucent covering overlying the multi point foot support;

FIG. 2 is a left side elevational view thereof, the broken lines showing the environment;

FIG. 3 is a rear elevational view thereof;

FIG. 4 is a right side elevational view thereof;

FIG. 5 is a front elevational view thereof.

FIG. 6 is a top plan view of a second embodiment of the present invention showing the translucent covering overlying the multi point foot support wherein a right side elevational is as shown in FIG. 2, a rear elevational view is as shown in FIG. 3, a left side elevational view is as shown in FIG. 4, and a front elevational view is as shown in FIG. 5. FIG. 7 is a top plan view of a third embodiment of the present invention showing the translucent covering overlying the multi point foot support, wherein a right side elevational is as shown in FIG. 2, a rear elevational view is as shown in FIG. 3, a left side elevational view is as shown in FIG. 4, and a front elevational view is as shown in FIG. 5;

FIG. 8 is a top left perspective view of the first embodiment of the present design as shown in FIG. 1;

FIG. 9 is a top left perspective view of the second embodiment of the present design shown in FIG. 6; and,

FIG. 10 is a top left perspective view of the third embodiment of the present design shown in FIG. 7.
